Primary Examiner—Brian N Vinson*(74) Attorney, Agent, or Firm*—Baker & McKenzie LLP**(57) CLAIM**

The ornamental design for a light fixture, as shown and described.

DESCRIPTION

FIG. 1 is a top perspective view of a light fixture in accordance with my design;

FIG. 2 is a top plan view of the light fixture in accordance with my design;

FIG. 3 a bottom plan view of the light fixture in accordance with my design; and,

FIG. 4 is a side elevation view of the light fixture in accordance with my design, all sides being substantially identical.

The broken-line disclosure of elements within the lamp shade structure are understood to represent portions of the article in which the design is embodied, but which form no part of the claimed design.
